WEBSTER M. ROBERTS AND PARK D. ROBERTS, OF ST. JOSEPH, MISSOURI.

TABLE-FORWARDING MECHANISM.

1,189,871.

Specification of Letters Patent.

Patented July 4, 1916.

Application filed October 3, 1914. Serial No. 864,965.

To all whom it may concern:

Be it known that we, WEBSTER M. ROBERTS and PARK D. ROBERTS, citizens of the United States, residing at St. Joseph, in the 5 county of Buchanan and State of Missouri, have invented certain new and useful Improvements in Table-Forwarding Mechanism; and we do declare the following to be a full, clear, and exact description of 10 the invention, such as will enable others skilled in the art to which it appertains to make and use the same, reference being had to the accompanying drawings, and to the letters and figures of reference marked 15 thereon, which form a part of this specification.

Our invention relates to table forwarding mechanism, and more particularly to mechanism for imparting step by step motion to a rotary table; the principal object of the invention being to provide a device whereby a rotary table may be intermittently forwarded a predetermined distance and locked after each movement. In accomplishing this object we have provided the improved details of structure herein- 25 after described and illustrated in the accompanying drawings, wherein:—

Figure I is a perspective view of a rotary table provided with a forwarding mechanism constructed in accordance with our invention. Fig. II is a plan view of the forwarding mechanism, showing a portion of the table. Fig. III is an enlarged 35 sectional view of the forwarding pawl; the functional position thereof being shown in dotted lines. Fig. IV is a detail perspective view of a portion of the under face of the table.

Referring more in detail to the parts:— 40 1 designates a pedestal, or the like, having a central shaft 2, and revolutely mounted on said shaft is a table 3 which may be of any suitable construction, but preferably 45 comprises a skeleton frame having inner and outer rings 4 and 5 and a hub 6 having a plurality of spokes 7 that join the rings together and form an integral structure. Integral with the under face of the inner 50 ring 4 are spaced teeth 9, the purpose of which will be presently described.

Rigidly mounted adjacent the pedestal 1 is a frame 10 comprising standards 11 which are connected near the vertical centers by a 55 crossbar 12, and at the top by a crossbar 13; the latter bar being adapted to lie a

short distance beneath the under face of the ring 4.

Slidably mounted in the brackets 15 on the crossbar 13, and immediately beneath the ring 4 is an arc-shaped bar 16, of the same curvature as the said ring, and pivotally mounted between the ribs 17 on said bar is an angular pawl 18, one leg of which normally lies between the ribs 17 and is 60 adapted to engage the teeth 9 and the other leg of which projects downwardly through a slot 20 in the bar. Integral with the pawl 18 is a stop 21 which is adapted to contact with the bar 16 to limit the movement of 65 the pawl, as clearly shown in Fig. III.

Revolutely mounted in the frame 10 is a shaft 22, having an eccentric disk 23 which carries a band 24 and rod 25, the latter being connected with the angular pawl 18 by 70 means of a universal coupling 26.

Mounted near one end of the bar 13 is a bracket 27 in which is pivotally mounted a latch 28 having a notch 29 adapted to engage any one of the teeth 9 of the table. 75

The latch 28 is yieldingly tensioned upwardly by a coil spring 30 which bears against a bracket 31 on the crossbar 13 and which surrounds a rod 32 that is connected with the latch 28 and with a bell crank lever 80 33; the latter being pivotally mounted in a bracket 34 on the crossbar 12 and adapted for engagement by a laterally extending boss 35 on the eccentric band 24.

In using the device, the shaft 22 and eccentric disk 23 are revolved by any suitable means, such as a motor (not shown) so that the rod 25 is reciprocated. On the forward movement of the rod the angular pawl 18 is forced between ribs 17 and stopped so that continued movement of the eccentric causes the arc-shaped bar 16 to move in its brackets 15 to the end of its stroke. When the eccentric is nearing the backward limit of movement the boss 35 engages the bell crank lever 33, moves the rod 32 and the latch 27 downwardly against the tension of the spring 30 to unlock the table. As the eccentric continues to revolve, the rod 25 is drawn forward so that the angular pawl is 95 moved against the shoulder 21 and against the teeth 9 of the table so that continued revolution of the eccentric draws the bar 16 and the table forward. As soon as the table has moved a short distance the boss 35 releases the lever 33 and the latch 27 rises under the influence of the spring 30, so that 100 105 110

when the eccentric has moved the table to the limit of its travel, the latch automatically engages the next succeeding tooth 9 and locks the table against further movement until the cycle is repeated.

It is apparent that with the herein described mechanism, the table may be forwarded at regular intervals and an equal distance at each movement, and that it is 10 locked positively at the end of each step.

Having thus described our invention, what we claim as new therein, and desire to secure by Letters-Patent, is:—

1. The combination with a revolute member, of a sliding bar located adjacent the revolute member and provided with a slot, a pawl pivotally mounted on the bar and projecting through the slot, one arm of said pawl being adapted for engagement 15 with the revolute member, and an eccentric having link connection with the other arm of the pawl.

2. The combination with a revolute member, having teeth on its under face, of 25 an arctuate bar located beneath the toothed portion of the revolute member and adapted for movement in a path parallel therewith, a pawl pivotally mounted in the bar and having an arm adapted for engagement 30 with said teeth, an eccentric connected with the opposite arm of the pawl and adapted for positively moving the pawl to engagement with the teeth and advancing the revolute member upon forward movement of 35 the bar, and for positively disengaging the pawl and returning said bar, for the purpose set forth.

3. The combination with a revolute member, of a bar movable adjacent the revolute member, a pawl on said bar, an ec-

centric operatively connected with the pawl to positively induce engagement of the pawl with the revolute member and positively disengage the same, a lock for holding the revolute member during the period of disengagement of the pawl, and means operable by the eccentric for controlling the lock. 45

4. The combination with an annular revolute member having teeth formed thereon; of a pawl carrier mounted adjacent to said teeth and adapted to be moved in a path parallel therewith, said pawl carrier having a slot formed vertically through the central portion thereof; an angular pawl 55 oscillatably mounted in said slot, the upper portion of said pawl projecting thereabove while its lower portion extends below said pawl carrier, said upper portion being adapted to be moved from and into contact 60 with said teeth and to contact the upper surface of said pawl carrier for limiting the oscillation of said pawl in one direction; a stop formed on the rear surface of said pawl, said stop being in like manner adapt- 65 ed to limit oscillation of said pawl in the opposite direction; and reciprocatve driving means connected with the lower portion of said pawl whereby said pawl is oscillated and whereby the latter and the therewith 70 connected pawl carrier are reciprocatively moved.

In testimony whereof we affix our signatures in presence of two witnesses.
